SEALED ENGINE CONTAINER

Albert E. Kueppers, Paterson, N. J., assignor to
 Wright Aeronautical Corporation, a corpora-
 tion of New York

Application April 6, 1940, Serial No. 328,332

7 Claims. (Cl. 206—46)

This invention relates to shipping containers and particularly to a metallic packing case for machine assemblies such as radial cylinder aircraft engines.

Previous practice in packing and shipping engines of the above mentioned type has consisted in securing the engine upon a mounting plate which in turn is bolted to a wooden table forming part of the bottom of a wooden packing case, the edges of the case bottom having attachment points for the case top which is dropped over the engine and is firmly secured to the case bottom. Thereafter, handling of the case must be effected by rope slings or special vehicular equipment. Since the engine is approximately 50 inches in diameter and anywhere from 60 to 70 inches long, it is apparent that a rectangular wooden packing case to accommodate it is a very bulky object measuring generally, about 5 ft. to 6 ft. square and 6 to 7 ft. high. Since the engines are shipped by rail or boat, the case must be very sturdy and accordingly is fabricated with great care and of high grade materials, and a further requirement is that when engines are shipped in these cases by boat, the case must be completely lined with waterproof material and the engine itself must be well covered with an anti-rust compound. By changes in temperature of the atmosphere, there is a certain amount of breathing of air into and out of the case, tending to increase the moisture content therein which, unless proper protection is given to the parts, obviously will cause corrosion and rust. The wooden packing cases above described must be of such sturdy construction that they weigh a great deal—of the order of 1,000 pounds or more.

It is an object of this invention to provide a metallic packing case suitable for aircraft engines which may be fitted more closely to the outline of the engine thus to occupy considerably less bulk and also to provide a metal casting which may be hermetically sealed to prohibit the entrance of moisture and to avoid the necessity for the previously necessary anti-rusting preparation.

Another object is to provide a metallic engine container which is relatively light in weight but structurally of sufficient strength to safely carry the engine without danger of damage to the more or less delicate parts thereof when the packed engine is given a normal, somewhat rough, handling common to transferring cargoes to and from ships and rail equipment.

Still another object of the invention is to pro-

vide a sealed, leak-proof container which is floatable on water with the engine packed therein. A case of this character may be floated ashore from ships instead of handled by rigging and lighters, which at times may be a great convenience.

It is appreciated that in the past steel drums have been used as containers for liquids and semi-solid compounds, but it is believed that the use of steel drums of the character hereinafter disclosed as a packing case for complex machine mechanisms, comprises a novel combination.

Objects of the invention will be apparent from the above discussion and further objects will become apparent in reading the annexed detailed description in connection with the drawing, in which:

Fig. 1 is a section through a packing container according to the invention;

Fig. 2 is a section on the line 2—2 of Fig. 1;

Fig. 3 is a section of the packing container nested for compact shipping with an engine therein; and

Fig. 4 is a fragmentary section through a portion of the container showing an alternative means for securing the container parts to one another.

A typical radial cylinder engine is shown in dotted lines at 10, and a conventional mounting provision for the engine comprises a plurality of bosses 11 circumferentially arranged around the principal axis of the engine. These bosses serve as a means for mounting the engine upon an aircraft and also serve as a means for mounting the engine upon a mounting member or plate 12 provided, as shown in Fig. 2, with a central cutout through which the rear section 13 of the engine may be passed and with lugs 14 registering with the bosses 11 so that the lugs and bosses may be secured by bolts 15. The member 12 is preferably of circular form concentric with the engine axis, and is of a diameter somewhat greater than the diameter of the engine, the periphery of the plate having a plurality of bolt holes, as shown.

The packing container per se comprises a central section 16 of drum form with flanges 19 at each end, and end sections 17 and 18 of cup form which have flanges 20 and 21 at their open ends, the diameter of the several sections 16, 17, and 18 being sufficient to embrace the engine and of a diameter equal to the diameter of the plate 12. When the engine is to be packed, the bottom cup section 17 is placed on its end on the floor, the plate 12 is disposed on the open end

thereof with a gasket 23 between the member 17 and the plate. The engine is then placed upon the plate and secured thereto, and the drum section 16 is disposed thereover, with the gasket 24 between the bottom flange 19 and the plate 12. Thereupon, securing bolts 25 are assembled to clamp the flanges 19 and 20 securely against the gaskets and mounting plate. Now, if the engine has considerable overhang from the mounting plate, a steadyng bushing 28 may be placed over the engine propeller shaft and a guide plate 29 slipped over the bushing, said plate having a periphery similar to the plate 12 so that it rests upon the upper flange of the plate 16. Thereafter, the member 18 is assembled, as shown, and is bolted at its flanges to the upper flange of the drum 16 so that the plate 29 is firmly secured. It will be obvious that the engine is rigidly supported within the drum and that the drum is a unitary structure which may be readily handled by conventional slings or other handling equipment. To facilitate drum handling, the end sections 17 and 18 may be provided with lifting eyes 31 to receive hooks of lifting equipment. For local handling, the drum may readily be rolled upon its flanges without the necessity of special truck equipment which has heretofore been necessary, and the drum may be upended for unpacking by a simple hoist which will subsequently be used to lift the engine out of the case when the case has been opened.

It is obvious that when assembled, the drum comprises a leak-proof, hermetically sealed, container. Preliminary designs of the drum contemplate the use of $\frac{3}{16}$ " or $\frac{1}{4}$ " boiler plate or the like which will give adequate strength to the assembly without excessive weight, the weight of the drum suitable for the conventional engine being of the order of 900 pounds which is less than the weight of material necessary for the conventional wooden rectangular case. In the drawing, the thickness of material forming the drum is exaggerated.

As a further convenience, in shipping the containers empty, I contemplate making the drum section 16 of full diameter with the end sections 17 and 18 of sufficiently smaller external diameter so that they will sleeve into the drum section in the manner shown in Fig. 3, so that the cubical content of an empty drum, ready for shipment, is only one-third as great as the cubical content of the container when the engine is packed therein. The end sections 17 and 18 may have cylindrical sides, as shown, or alternately may be of conical shape so that they nest one within the other.

For a drum of the size contemplated, namely, about 60 inches in diameter, it is apparent that, with $\frac{3}{16}$ " or $\frac{1}{4}$ " material, a great number of securing bolts 25 would have to be used in order to hermetically seal the flanges. The large plurality of bolts may be readily secured or removed by the use of power driven speed wrenches which are now commercially available but if desired, an alternate means of securing the flanges may be utilized after the manner of Fig. 4 which eliminates nearly all of the flange bolts. In Fig. 4, the case sections 16' and 18' correspond to the sections 16 and 18 of Fig. 1, and the mounting plate 29 is placed between bulb flanges 34 and 35 of the case sections. An annular inturned split channel member 36 is snapped around the drum flanges and is of such width as to force the flanges 34 and 35 firmly against the edge of the plate 29 and the gaskets which would be

used between the flanges and plate, the annulus being readily assembled by progressively beating it over the flanges with a mallet or the like. When the annulus fully embraces the flanges, it may be given additional security against inadvertent displacement by one or more through bolts 37 which pass through appropriate holes drilled through the annulus flanges, through the drum flanges, and through the mounting plate. Preferably, about four or five such bolts would be used, one adjacent each end of the split annulus 34, and two or three spaced around the periphery of the drum to serve as locators for the plate 29 and the drum sections against relative radial displacement. Alternate clamping means for the drum sections will be readily apparent to those skilled in the art, but it is believed that the two clamping means shown in Figs. 1 and 4 would be both practical and appropriate for an arrangement of this character.

As shown in Fig. 3, the smaller end section 18 of the packing case is provided with a recess 38 to receive the reentrant portion of the drum section 17 at the point where the lifting eye 31 is located.

In engines which do not have great overhang from their mounting planes, the steadyng bushing 28 and the plate 29 may be redundant in which case they may be omitted and the flanges of the drum sections 16 and 18 secured directly to one another with only a single gasket therebetween.

It will be seen that a drum of the character shown may be fitted much more closely to the external dimensions of an engine than the wooden rectangular packing cases of prior practice so that the total volume occupied by the packed container will be substantially less than was heretofore necessary. This is a distinct advantage particularly in ship transportation, since bulk is as much of a factor in determining freight rates as is weight—the usual ship ton is either 2,000 pounds or 40 cubic feet, whichever is reached first, so that a saving of from 20% to 40% in volume will afford a corresponding saving in shipping cost.

As to flotation of a packed container, there is ample margin since the packet weight of the engine will be approximately 3,000 pounds where the displacement of an equal volume of water would be of the order of 8,000 pounds.

While I have described my invention in detail in its present preferred embodiment, it will be obvious to those skilled in the art, after understanding my invention, that various changes and modifications may be made therein without departing from the spirit or scope thereof. I aim in the appended claims to cover all such modifications and changes.

I claim as my invention:

1. A metallic cylindrical drum container comprising cylindrical parts securable at their edges to one another, whereby the drum when opened parts between its ends, a mounting plate to which a packed article is secured having a perforated peripheral portion engageable between the edges of said cylindrical parts, said cylindrical part edges comprising perforate flanges, and bolts passing through the plate and flange perforations securing the flanges and mounting plate periphery together.

2. A metallic cylindrical drum container comprising cylindrical parts securable at their edges to one another, whereby the drum when opened parts between its ends, a mounting plate to which

a packed article is secured, having a peripheral portion engageable between the edges of said cylindrical parts, said cylindrical part edges comprising annular flanges between which the mounting plate is disposed, and means to clamp the flanges and plate against relative displacement comprising a plurality of bolts or the like passing through the flanges and plate.

3. A metallic cylindrical drum container comprising cylindrical parts securable at their edges to one another, whereby the drum when opened parts between its ends, a mounting plate to which a packed article is secured, having a peripheral portion engageable between the edges of said cylindrical parts, said cylindrical part edges comprising annular flanges between which the mounting plate is disposed, and a clamp band embracing the flanges and securing them against relative displacement.

4. A metallic cylindrical drum container comprising cylindrical parts securable at their edges to one another, whereby the drum when opened parts between its ends, a mounting plate to which a packed article is secured, having a peripheral portion engageable between the edges of said cylindrical parts, and means wrapped around and secured to the edges of the cylindrical parts for holding the parts and the mounting plate together as a unitary assembly.

5. A packing case for a radial aircraft engine comprising a circular mounting member secured to the engine substantially concentric therewith, a circular pilot member loosely engaging the concentric power shaft at the front of the engine, a drum embracing the engine and engaging at its ends with said members, cup elements covering the front and rear of the engine and engag-

ing at their edges with respective members, and means to secure said members, drum and elements to one another to comprise a unitary carrying case for said engine.

6. A packing case for radial aircraft engine comprising a circular mounting member secured to the engine substantially concentric therewith, a circular pilot member loosely engaging the concentric power shaft at the front of the engine, a drum embracing the engine and engaging at its ends with said members, cup elements covering the front and rear of the engine and engaging at their edges with respective members, and means to secure said members, drum and elements to one another to comprise a unitary carrying case for said engine, said cups and drum edges comprising flanges, and said securing means comprising bolts engaging and clamping the flanges upon the members.

7. A packing case for a radial aircraft engine comprising a circular mounting member secured to the engine substantially concentric therewith, a circular pilot member loosely engaging the concentric power shaft at the front of the engine, a drum embracing the engine and engaging at its ends with said members, cup elements covering the front and rear of the engine and engaging at their edges with respective members, and means to secure said members, drum and elements to one another to comprise a unitary carrying case for said engine, said cups and drum edges comprising flanges, and said securing means comprising annular channel members embracing the flanges and members to secure same against displacement.

ALBERT E. KUEPPERS.
